PUTTING GAME TARGET

Kenneth G. Suesens, 1254 Main Ave., Sheboygan, Wis.

Filed May 7, 1964, Ser. No. 79,868

Term of patent 3½ years

(Cl. D34—5)

The single figure is a perspective view of a putting game target embodying my new design. The surfaces not visible are plain.

The dominant features of my design reside in those portions thereof shown in full lines.

I claim:

The ornamental design for a putting game target, as shown and described.
